FIG.1

FIG.2

FIG.3

FIG.5

FIG. 1 is a perspective view of a recreation vehicle showing my new design, the sleeper portion being illustrated in its outwardly pivoted position;

FIG. 2 is a top plan view thereof;

FIG. 3 is a left side elevational view thereof, the right side elevational view being the same except for omission of any sleeper portion on the right side;

FIG. 4 is a rear elevational view thereof with the sleeper portion in its outwardly pivoted position; and

FIG. 5 is a front elevational view thereof with the sleeper portion in its outwardly pivoted position.

The characteristic feature of my design resides in the specific configuration of the side projecting sleeper portion in combination with the vehicle as shown.

I claim:

The ornamental design for a recreation vehicle, substantially as shown and described.
